UNITED STATES PATENT OFFICE.

JOHN KNIERIEM, OF GLENDALE, NEW YORK, ASSIGNOR TO METROPOLITAN-COLUMBIA MFG. CO., INC., A CORPORATION OF NEW YORK.

DESIGN FOR A LIGHTING-FIXTURE PART.

Application filed September 14, 1926. Serial No. 19,058. Term of patent 3½ years.

To all whom it may concern:

Be it known that I, JOHN KNIERIEM, a citizen of the United States, and a resident of Glendale, county of Queens, and State of New York, have invented a new, original, and ornamental Design for a Lighting-Fixture Part, of which the following is a specification, reference being had to the accompanying drawing, forming a part hereof.

In these drawings:

Figure 1 is an inverted plan view of the

lighting fixture part, the part shown in full line outline being ornamented in the same manner as the part more fully illustrated; and

Figure 2 is a diagrammatic side elevational view of the lighting fixture part.

I claim:

The ornamental design for a lighting fixture part substantially as shown and described.

JOHN KNIERIEM.
